US0D1049208S

(12) **United States Design Patent** (10) **Patent No.:** **US D1,049,208 S**
Tillet (45) **Date of Patent:** **** Oct. 29, 2024**

(54) **GOGGLES**

(71) Applicant: **BOLLE PROTECTION**, Villeurbanne (FR)

(72) Inventor: **Benoit Tillet**, Collonges-au-Mont-d'Or (FR)

(**) Term: **15 Years**

(21) Appl. No.: **35/520,118**

(22) Filed: **Feb. 8, 2024**

(80) **Hague Agreement Data**

Int. Filing Date: **Feb. 8, 2024**

Int. Reg. No.: **DM/235189**

Int. Reg. Date: **Feb. 8, 2024**

Int. Reg. Pub. Date: **Feb. 23, 2024**

(51) **LOC (14) Cl.** **16-06**

(52) **U.S. Cl.**

USPC **D16/315**

(58) **Field of Classification Search**

USPC D16/300, 314, 315, 319, 326, 327, 329; D24/110.2; D29/102-110

CPC . G02B 2027/0178; G02C 5/003; G02C 5/008
